UNITED STATES PATENT OFFICE.

GIANNI CAPRONI, OF MILAN, ITALY.

MULTIPLANE FLYING-MACHINE.

1,356,850.

Specification of Letters Patent. Patented Oct. 26, 1920.

Application filed February 13, 1920. Serial No. 358,446.

To all whom it may concern:

Be it known that I, GIANNI CAPRONI, engineer, subject of the Kingdom of Italy, residing at Milan, Via Durini 24, have invented 5 certain new and useful Improvements in and Relating to Multiplane Flying-Machines, of which the following is a specification.

The present invention relates to flying machines of the type where a plurality of 10 multiplane groups are combined with a plurality of longitudinal girders or fuselages and a car, which are tied and fastened to the frameworks of the multiplane groups more particularly with reference to my co- 15 pending application of the same date.

In a flying machine of the above type the invention consists in arranging the engines at the ends of the side girders or fuselages of the machine.

20 The accompanying drawing represents a plan view of a flying machine, showing the arrangement of the engines according to the present invention.

A detailed specification of the flying machine is given in my co-pending application of the same date, mentioned above, and is not necessary for the understanding of the present invention. Generally speaking the machine comprises multiplane groups —1—, 25 —2—, —3— combined with girders or fuselages —4— and stay cables —6— and other

means for sustaining a car —7— and floats —8—.

According to this invention the engines —9—, —11—, —13— and —15— are arranged at the ends of the side girders or 35 fuselages —4— and other engines —10—, —12—, —14— and —16— are arranged centrally relatively to the front and the rear multiplane group in separate nacelles secured under the middle planes. 40

In the construction where intermediate girders or fuselages are mounted between the outer ones —4— it is to be understood that no engines will be mounted upon such intermediate girders or fuselages. 45

Having now particularly described and ascertained the nature of my said invention and in what manner the same is to be performed, I declare that what I claim is:

In a flying machine including a plurality of multiplane groups and spaced parallel and longitudinally disposed girders connecting the groups, cock pits provided at the ends of the girders, engines mounted in the cock pits, independent nacelles mounted in 55 the front and rear multiplane groups and additional engines mounted in the nacelles.

In testimony whereof I have affixed my signature.

GIANNI CAPRONI.
